UNITED STATES PATENT OFFICE

CHARLES FREDERICK REGINALD JEAVONS, OF LEICESTER, ENGLAND, ASSIGNOR TO
UNITED SHOE MACHINERY CORPORATION, OF PATERSON, NEW JERSEY, A COR-
PORATION OF NEW JERSEY

FASTENING INSERTING MACHINE

Application filed August 5, 1930, Serial No. 473,150, and in Great Britain September 19, 1929.

This invention relates to fastening inserting machines and is illustrated herein as embodied in a machine for attaching to shoes or to heel bases rubber heels, top pieces or like members which require their fastenings to be driven at definite locations.

Rubber heels of the type referred to above commonly have their tread surfaces provided with a series of conical recesses terminating in cylindrical nail-receiving holes which are surrounded by small metallic washers spaced from the tread surface of the heels and arranged to receive the heads of the nails in order to provide solid bearings therefor. It will be evident that accurate passage of the fastenings through the washers is essential to proper fastening of the rubber heels.

Metal heel tips afford another example of members which require fastenings to be driven at definite locations, in this instance through holes formed in the metal tips when they are made. Because of the character of the material from which the tips are made it is necessary that each nail receiving hole formed therein be positioned accurately relatively to the line of drive of the fastenings in order properly to secure the tips to their associated parts.

In view of the above it is an object of the present invention to provide an improved fastening inserting machine in which the work may be positioned properly relatively to the line of drive of the fastenings by means of a single member which is operable also to insert fastenings into the work and which is illustrated herein as a nail-inserting driver.

Inasmuch as this invention is of particular utility in machines of the general character disclosed in U. S. Letters Patent No. 490,624, granted January 24, 1893, on an application of Louis Goddu, it will be herein disclosed as embodied in a machine of this type although it will be understood that the invention is not limited to use in connection with machines of this character.

Machines of this type are provided with clutch mechanism by means of which the operation of the fastening inserting instrumentalities may be initiated and suspended.

50 A work support is caused to press the work

against an abutment or presser plate during the insertion of the fastenings and means is provided for relieving this pressure to allow the work to be fed. Such machines may be provided with separate treadles to control the raising and lowering of the work support for the removal and replacement of the work and the starting and stopping of the fastening inserting instrumentalities. Since in nailing shoe parts of the type referred to above it is necessary for the operator to locate the work for each nail to be driven in order that the nails will be driven accurately through the nail receiving holes formed in the work, the machine is usually stopped after each nail is inserted. Also the spacing between various nail locations in a rubber heel, top piece or like member ordinarily differs and consequently a set mechanical feed of the work cannot usually be employed.

In the illustrated machine and according to an important feature of the invention, the driver member is arranged to come to rest in such a position that the end of the driver may be used as a gage to position a nail receiving hole formed in the work in alignment with the line of drive of the fastenings. Means, illustrated as a work support, is arranged to force the work against a presser plate with the work located by the driver prior to each fastening inserting operation and to be moved into pressure relieving position after a fastening has been inserted into the work so that the work may be fed to a fresh location by the operator.

With the above and other objects and features in view the invention will now be described in connection with the accompanying drawings and will be pointed out in the claims.

In the drawings,
Fig. 1 is a front view of the head of a fastening inserting machine embodying the present invention;
Fig. 2 is a side elevation of the entire machine partly in section to show more clearly the construction thereof; and
Fig. 3 is a diagrammatic view showing the timing of the cam motion of a number of the parts of the machine.

As usual in machines of the type hereinbefore referred to the illustrated machine, like the machine of said Letters Patent, is provided with a raceway adapted to receive 5 previously formed headed nails from a hopper, a separator for separating the endmost nail of a line of nails in the raceway and movable to present the nail to the operation of the nail driver. In the illustrated machine, 10 however, the awl, the awl supporting mechanism and the mechanism for producing the swing of the head of the machine which imparts the work feeding movement to the awl are removed. In describing the present 15 invention it is unnecessary to set forth in detail the construction and mode of operation of many of the parts of the machine and for a full description of such parts reference may be had to the said Letters Patent.

20 The illustrated machine is provided with a main frame or column 10 carrying at its upper end a head 12 and with a secondary column 14 carrying a work support illustrated as a last pin 16. The head 12 carries a cam shaft 18 from which the various parts of the machine are operated. A driver bar 20 carrying a driver 22 is moved upwardly by means of a lifting cam 24 which engages a block 26 carried by the driver bar 20. A spring 28 anchored at one end to a stationary part of the head of the machine and connected at the other end by a link 30 with the driver bar 20 forces the driver bar 20 and driver 22 downwardly when the cam 24 passes out from under the block 26, thus driving a nail into the work, and is compressed as the cam 24 lifts the driver bar 20. The work support 16 is arranged to clamp the work against a presser plate 32 which limits its upward 25 movement. The work support 16 is moved downwardly from a pressure applying position after the driver 20 has driven a fastener to allow the work to be fed by the operator and upwardly into a pressure applying position to clamp the work against the presser plate 32 prior to the fastening inserting operation by suitable release mechanism, for example as disclosed in Letters Patent of the United States No. 265,227, granted September 26, 1882, on an application of Louis Goddu, also driven from cam shaft 18 by means of a cam 34. The cam 34 is connected with a horn depressing lever 42, having its fulcrum at 44 and connected at 46 to the lower 30 end of a work supporting shaft 48 carrying at its upper end the work support 16, by means of a ratchet and pawl arrangement 40 which allows the work support to be depressed a predetermined amount after each fastening is inserted notwithstanding variations in the thickness of the work, as more fully set forth in Letters Patent No. 265,227. The operator may depress the work support to place the work thereon by means of a foot 35 treadle 50 pivoted at 44 and having its rear

end engaging the lever 42 at the rear of its fulcrum.

The driver 22 is set in such a position vertically in its carrying bar 20 that the lower end of the driver 22 projects a definite distance below the work engaging face of the presser plate 32 at the conclusion of the driver stroke. The front of this presser plate 32 is preferably cut away so that the operator may easily see the lower end of the driver 22. The illustrated machine, like the machine of Letters Patent No. 490,624, is provided with the usual clutch controlling mechanism by means of which a driving pulley 52 rotatably mounted upon the shaft 18 is caused to move axially on the shaft 18 to engage a clutch member fixed to the shaft 18 when starting treadle 54 is depressed by the operator. In order to bring the machine to rest promptly after the clutch is disengaged, the illustrated machine is also provided with the usual brake operating mechanism comprising a cam 56 fast to the shaft 18, a cam lever 58, and a brake band 60. The brake band 60 is arranged to engage the periphery of the cam 34 to check rotation of the shaft 18 after each nail has been driven. The relation of the timing of various parts of the machine, as shown in Fig. 3, is such that the machine is arranged to come to a stop, after each nail has been driven, with the end of the driver 22 projecting below the work engaging surface of the presser plate 32 and the work support 16 depressed sufficiently to allow the operator to move the work to a fresh position. The driver 22 in its inoperative position may be used as a gage to locate the work by causing the end of the driver to be threaded into a recess such as that which usually occurs above each washer in the tread surface of a rubber heel.

In operation the operator moves the work support 16 downwardly by means of the treadle 50 to a work receiving position and places upon the last pin 16 a shoe mounted upon a last and then positions an unattached rubber heel on the heel-seat portion of the sole of the shoe. When the treadle 50 is released, the work support 16 moves upwardly, not, however, sufficiently to apply a clamping pressure to the shoe and heel, and the operator, by the end of the driver 22, locates a recess in the rubber heel which requires a fastener. Then, by depressing the treadle 54, he causes the machine to drive a single nail in the selected position. When the treadle 54 is released the machine will automatically stop with the parts in the relation above described and as is shown in Fig. 1.

It will be understood that certain features of the invention are not limited to the particular type of work support shown since obviously any type of work support adapted to support a shoe or a shoe part may be used without departing from the spirit of the in-

vention; for example, a horn may be used instead of a last pin when it is desired to fasten rubber heels to loose or unattached heel bases.

Having described my invention, what I claim as new and desire to secure by Letters Patent of the United States is:—

1. A fastening inserting machine having, in combination, means constructed and arranged to enter a fastening receiving recess in a work piece to position said recess in the line of drive of the fastenings, means operating to clamp the work, and means for thereafter operating the first-named means to insert a fastening into the work.

2. A fastening inserting machine having, in combination, means for positioning a recess in a work piece in fastening receiving position, means for clamping said work piece in said position, and means for thereafter reciprocating the first-named means to insert a fastening into said recess in the work.

3. A fastening inserting machine having, in combination, a single member arranged to locate a fastening receiving hole in a work piece in fastening receiving position and to insert a fastening in said hole, means operating to clamp the work, and means for thereafter operating the locating member to insert a fastening into said fastening receiving hole in the work.

4. In a fastening inserting machine the combination with a presser plate and a work support movable toward and from said presser plate and arranged to clamp the work therebetween of a single member arranged to engage the work on the support and thereby to position the work properly relatively to the line of drive of the fastenings prior to the work clamping movement of the work support and means for thereafter reciprocating said member to drive fastenings into the work after the support has been moved into work clamping position.

5. A fastening inserting machine having, in combination, a single member arranged to enter a recess in the work to position said recess in alinement with the line of drive of the fastenings, means for clamping the work in said alined position, and means for thereafter operating the first-named member to drive a fastening into said recess in the work.

6. A fastening inserting machine having, in combination, a presser plate, a work support movable toward and from said presser plate and arranged to clamp the work against the presser plate while the fastenings are inserted, a fastening inserting driver constructed and arranged to extend below said presser plate when the work support is away from work clamping position and the machine is at rest to facilitate positioning of the work on the support, and means for reciprocating the driver, after the support has

been moved into work clamping position, to insert a fastening into the work.

7. A fastening inserting machine having, in combination, a presser plate, a work support movable toward and away from said presser plate and arranged to clamp the work against the presser plate, a driver arranged to extend below said presser plate when the machine is at rest to engage the work and to locate a fastening receiving hole formed in the work in alinement with the line of drive of the fastenings, and means for reciprocating the driver to insert a fastening into the work.

8. A fastening inserting machine having, in combination, means for inserting a fastening in a hole in a work piece, said means acting also as a gage and arranged to be threaded into a hole in a work piece to locate the hole in the line of drive of the driver, work clamping means, and means for reciprocating the inserting means to insert the fastening in the hole.

9. A fastening inserting machine having, in combination, a work support, a fastening inserting driver arranged to be threaded into an opening in the work to position said opening in alinement with the line of drive of the fastenings, a presser plate co-operating with the work support to clamp the work while the driver remains threaded therein, and means for reciprocating the driver to drive a fastening into the work.

10. A fastening inserting machine having, in combination, a presser plate, a work support, a fastening inserting and work locating driver arranged to enter a hole in a work piece to position said hole in alinement with the line of drive of the driver, means for reciprocating the driver thereby inserting a fastening in the hole in the work, and means for producing relative movement between the work support and the presser plate to clamp the work therebetween while the work remains located by the driver.

11. A fastening inserting machine having, in combination, a presser plate, a work support, a fastening inserting and work positioning driver arranged to engage the work and thereby to position the work properly relatively to the line of drive of the fastenings, means constructed and arranged to reciprocate the driver thereby inserting a fastening into the work, and means for operating the work support, said means being constructed and arranged to move the work support toward the presser plate to clamp the work therebetween during the fastening inserting operation and thereafter to depress the work support after a fastening has been inserted into the work.

12. A fastening inserting machine having, in combination, a presser plate, a throat member, a fastening inserting driver movable in said throat member and extending below the

work engaging face of said presser plate when the machine is at rest to facilitate positioning of the work relatively to the line of drive of the fastenings, a work support, means for moving the work support toward the presser plate to clamp the work therebetween, and means for operating the driver to insert a fastening into the work.

13. A fastening inserting machine having, 10 in combination, a stationary presser plate, a fastening inserting driver normally extending below the presser plate and arranged to engage the work and thereby to position the work properly relatively to the line of 15 drive of the driver, a work support, automatic means for operating the work support constructed and arranged to move the support into pressure applying position and to hold it in that position during the fastening 20 inserting operation and, after a fastening has been inserted into the work, to move the work support into pressure relieving position, and means under the control of the operator for initiating movement of the last-named 25 means.

14. A fastening inserting machine having, 30 in combination, a throat member, a presser plate, a driver movable in said throat member and arranged to extend below said presser plate when the machine is at rest, a work support, a cam shaft, a cam carried by said shaft, and connections between the cam and said work support arranged to hold the work support in such a position when the machine is at 35 rest that the end of the driver may be used as a gage to locate a recess in the work in which a nail is to be inserted.

15. In a machine for inserting fastenings in rubber heels having nail receiving holes 40 formed therein surrounded by metallic washers to receive the heads of the fastenings, a presser plate, a work support, fastening inserting means comprising a driver arranged to engage the work and thereby to position 45 each nail receiving hole in alinement with the line of drive of the driver, automatic means for elevating the work support to clamp the work against the presser plate, means for presenting a fastening to the operation of the driver, and means for operating 50 the driver to insert a fastening into the work with the head of the fastening in engagement with the washer.

16. In a machine for inserting fastenings 55 in rubber heels having conical recesses formed in the tread surfaces thereof and terminating in cylindrical nail receiving holes surrounded by metallic washers to receive the heads of the fastenings, a work support, a 60 presser plate having a work engaging face formed thereon, and a fastening inserting driver extending through said presser plate and having its end projecting a predetermined distance beyond the work engaging 65 face of said presser plate when the machine

is at rest and arranged to gage the position of the work on the work support, whereby each nail receiving hole formed in the work may be positioned successively in alinement with the line of drive of the fastenings. 70

17. A fastening inserting machine having, in combination, a presser plate, a work support, operating means therefor constructed and arranged to move the support into and out of pressure applying position, a fastening inserting and work locating driver arranged to extend beyond said presser plate when the machine is at rest and to engage the work to position the work relatively to the line of drive of the fastenings, means 80 for maintaining the driver in said position during the pressure applying movement of the work support, and means for operating the last-named means to cause the driver to drive a fastening into the work. 85

In testimony whereof I have signed my name to this specification.

CHARLES FREDERICK REGINALD JEAVONS.
